UNITED STATES PATENT OFFICE.

GLADYS ROWLAND, OF NEW YORK, N. Y., ASSIGNOR TO SUSQUEHANNA SILK MILLS,
OF NEW YORK, N. Y., A CORPORATION OF NEW YORK.

DESIGN FOR A TEXTILE FABRIC.

60,822.

Specification for Design. Patented Apr. 11, 1922.

Application filed February 21, 1922. Serial No. 807. Term of patent 3½ years.

To all whom it may concern:

Be it known that I, GLADYS ROWLAND, a textile fabric showing my new design, citizen of the United States, residing at New York, in the county of New York and State of New York, have invented a new, original, and ornamental Design for a Textile Fabric, of which the following is a specification, reference being had therein to the accompanying drawings.

The figure is a plan view of a piece of

I claim:

The ornamental design for a textile fabric, as shown.

In testimony whereof I hereunto affix

GLADYS ROWLAND.
